ELECTROKINETIC TRANSDUCING METHOD
AND APPARATUS

Milton Williams, Houston, Tex.

Application October 25, 1949, Serial No. 123,494

5 Claims. (Cl. 171—330)

(Granted under the act of March 3, 1883, as
amended April 30, 1928; 370 O. G. 757)

1

This application is in part a continuation of my pending application Ser. No. 617,911 filed Sept. 21, 1945 and includes embodiments of my invention reported in my article entitled An Electrokinetic Transducer published in The Review of Scientific Instruments, vol. 19, No. 10, 640-646, October, 1948.

This invention relates to electrokinetic transducing methods and apparatus.

Electrokinetic phenomena are well known in the specialized branch of science dealing with the physics and chemistry of surfaces. As full an explanation of the effects as is known can be had by referring to any standard work in this field such as Colloid and Capillary Chemistry by H. Freundlich (translated from the 3rd German edition by H. S. Hatfield) published by E. P. Dutton. The subject is described in this volume under the title Capillary-Electrical Phenomena on pages 239 et seq. and is briefly summarized herewith.

There are four phenomena, generally designated as electrokinetic, involving the electrical forces set up by or applied to cause relative motion of solids and liquids in mutual contact: (1) electroosmosis: liquid is caused to move along walls of capillary tubes by the application of an E. M. F.; (2) cataphoresis or electrophoresis: solid particles move through relatively stationary liquids under the application of an E. M. F.; (3) stream or streaming potential: the E. M. F. set up by forcing liquid through capillary openings in a relatively stationary solid; (4) the Dorn effect: the production of a potential gradient by dropping solid particles through liquids. Of these electrokinetic effects, my invention is concerned primarily with electroosmosis and the stream potential. It has been determined that the magnitude of the stream potential is a direct function of, among other things, the dielectric constant of the liquid, the resistivity of the liquid and the "zeta potential" existing upon the association of the particular liquid with a particular solid. According to currently accepted theory, when a liquid comes in contact with the walls of a capillary opening in a solid, a double layer (perhaps of the order of molecular thickness) of electrical charges arises in the liquid, those of one sign adhering to the wall of the capillary, while at a slight distance therefrom in the liquid are aligned an equal number of charges of opposite sign. If the double layer is considered as a condenser, the potential between its plates is designed as the "zeta potential" and is characteristic for any combination of liquid and solid.

2

This invention makes use of what might be called an electrokinetic assembly including a solid medium, usually a porous disc or plug or diaphragm, through capillary openings in which a fluid flows, and a pair of electrodes, one on either side of the solid medium, that serve to transmit either to or from the assembly an electromotive force. Hereinafter the solid medium will be designated as an electrokinetic plug and the fluid as electrokinetic fluid or simply fluid. Essentially the invention involves the use of a fixed quantity or body of fluid arranged so that at least part of it passes through the electrokinetic plug and in so moving causes a restoring force to be applied to the body of liquid, which restoring force is a monotonic increasing function of the displacement of the liquid. A restoring force is a force that operates in a direction opposite to the displacement of fluid and tends to return the displaced fluid to its original position. Apparatus constructed according to the present invention involves the provision of such structure as will contain the body of liquid and will produce the aforescribed restoring force.

25 The principle of the invention can be embodied in transducing methods or apparatus that, broadly speaking, inter-convert mechanical and electrical energy. Specific embodiments, as will be seen, are adapted particularly for either one conversion or the other. The principle is useful in the construction of measuring devices, such as devices for measuring, for example, the characteristics of pressure changes in a region, the rate of climb of aircraft, or the rate of submergence of submarines and also is useful in constructing such transducing devices as hydrophones, phonograph pickups, seismic pickups and the like. The methods and apparatus can, of course, be used for measuring variations of any quantities which can be translated into relative displacements of the electrokinetic fluid and electrokinetic assembly.

30 Objects of the invention are to provide methods and apparatus for transducing using the electrokinetic effect, wherein the method and apparatus will be reliable over wide ranges of conditions.

35 Other objects and many of the attendant advantages of this invention will be readily appreciated as the same becomes better understood by reference to the following detailed description when considered in connection with the accompanying drawings wherein

40 Fig. 1 is a diagrammatic view of an open U-tube apparatus embodying the invention;

Fig. 2 is a closed U-tube apparatus embodying the invention;

Fig. 3 is an embodiment of the invention in a rate of climb instrument;

Fig. 4 is an improved transducer adapted for observing pressure fluctuations in pipe lines and the like;

Fig. 5 is a hydrophone;

Fig. 6 is a phonograph pickup; and

Fig. 7 is a seismic pickup.

The figures will now be taken up in more detail. Fig. 1 shows a U-tube 2 containing an electrokinetic assembly that includes an electrokinetic plug 4, a fixed quantity of fluid 6, and a pair of electrodes 8 and 10 disposed one on either side of the porous plug 4. The electrodes are connected to a potential measuring device 12 which can be of varied construction. The instrument 12 can be a galvanometer, a vacuum tube voltmeter, an oscilloscope (preferably adapted for recording), an electrometer, a bridge apparatus or other equipment for measuring voltage while preferably drawing little or no current. Hereinafter, the instrument 12, and its counterparts in other figures may be denominated simply as a voltmeter or a meter. The U-tube 2 can be of uniform diameter or can be provided with enlarged sections or reservoirs 14 and 16. One end 18 of the U-tube is shown as being open to the atmosphere while the other end 20 is shown connected to a region R, the characteristics of the pressure changes in which the apparatus is designed to measure. Under the conditions illustrated in Fig. 1, where the levels 22 and 24 of the fluid in the reservoirs 14 and 16 respectively are identical, the pressure in the region R is, of course, atmospheric. An increase in pressure in the region R will cause the fluid 6 to be displaced with a corresponding decrease in the height of the fluid in the arm 28 of the U-tube. During this displacement or flow of fluid a portion of the body of fluid 6 necessarily passes through the plug 4 and thereupon generates a streaming potential that is measured by the voltmeter 12. The magnitude of the streaming potential is proportional to the rate of flow of fluid through the plug which in turn depends on the pressure difference across the plug. The difference in levels of the fluid in reservoirs 14 and 16 produced by the displacement of the fluid causes a restoring force to be exerted on the body of fluid which is a monotonic increasing function of the displacement. This force, of course, is produced by the action of gravity on the fluid. A decrease in pressure in the region R causes a flow of fluid in the opposite direction with a rise in the level 24 and a lowering of the level 22. The dimensions of the U-tube and quantity of fluid are naturally so chosen that the anticipated changes of pressure in the region R will never be such as to cause the fluid to leave the confines of the U-tube 2. If desired, a flexible diaphragm can be inserted in the U-tube 2, for example, in the reservoir 16 at the level 24, to separate the fluid 6 from the fluid in the region R.

Fig. 2 illustrates another embodiment of the invention generally in the form of a closed U-tube 30 having an electrokinetic assembly including a porous plug 32 (through which flows part of a body of fluid 34) and a pair of electrodes 36 and 38. The electrodes are connected to a voltmeter 40. The arm 42 of the U-tube is shown as being provided, preferably but not necessarily, with an enlarged section or reservoir 44 connected to a region in which pressure changes are to be observed. This region can be of varied character

but is illustrated as a pipe line or conduit 46 having valves 48 and 50 on either side of the junction between the arm 42 and the conduit 46. The other arm 52 of the U-tube terminates in a closed chamber 54. This chamber can be rigid and substantially inflexible but is illustrated as being a resilient diaphragm in the form of a metal bellows. It will be apparent that an increase of pressure in the region 48 will cause a displacement of the fluid 34 with a corresponding lowering of the level 56 and rise in the level 58. This displacement involves a flow of fluid through the plug 32 which is reflected as a voltage reading appearing on the instrument 40. In this instance the restoring force is composed of several components including the force produced by the increased head of fluid in the arm 52, the force produced by the increased pressure of the compressed gas such as air 60 in the region above the fluid level in the chamber 54, and the force produced in the metal of the bellows 54 by its distortion. A decrease in pressure in the region 46 will cause a flow of fluid 34 in the opposite direction again producing a reading on the instrument 40. As in the embodiment in Fig. 1, here, also, a diaphragm can be used in the reservoir 44 to separate the fluid 34 from the material flowing in the conduit 46. The conduit 46 is used diagrammatically to represent such conduits as oil or gas pipe lines but might also be merely a tank or other container. In the apparatus shown in Fig. 2, if 40 is a voltmeter, for example, it reads zero when the pressure in the conduit 46 reaches a steady state constant value. Thus it can be said that, in general, this embodiment of the invention is not a pressure measuring device but is a device responsive to changes in pressure and can be designed, by so proportioning its parts, to indicate over a desired range the rate of change of pressure in the conduits 46.

Fig. 3 shows another embodiment of the invention particularly adapted for measuring rate of climb of aircraft. In this figure the U-tube of the preceding figures has been modified so that what might be considered one arm 62 thereof surrounds the other arm 64. In the drawing the arms are shown as cylinders but might be of other configuration. The electrokinetic assembly, comprising the porous plug 66 and electrodes 68 and 70, is inserted between the two arms 62 and 64. The electrodes are connected to a meter 72 to measure the voltage generated upon flow of the fluid through the plug 66. The arms 62 and 64 are arranged concentrically for the purpose of preventing extraneous effects due to the accumulation of a difference in hydrostatic head that might be caused by tilting of the apparatus when mounted in an aircraft. Preferably the cross section of the annulus between the cylinders is the same as the interior cross-section of the inner cylinder. To avoid disturbances caused by temperature changes it might be desirable to enclose the apparatus in a thermally insulated container 74. The arm 64 terminates in a metal bellows or thin rubber diaphragm or the like 76. The air in the region 78 is sealed from the influence of the ambient atmospheric pressure by the wall 80 of the U-tube, whereas the air in the region 82 is subject to the influence of the atmospheric pressure through the medium of the metal bellows 76. When the apparatus is mounted in an aircraft the bellows 76 expands as the aircraft climbs because the ambient atmospheric pressure on the outside of the bellows is decreasing and the air in the region 78, originally at sea level atmospheric pres-

sure, expands forcing the fluid to rise in the arm 64. The meter 72 reads only during the flow of fluid and therefore does not read when the system reaches a steady state equilibrium. It is therefore apparent that the reading of the meter 72 is an indication of the rate of climb of an aircraft. In this embodiment, also, the restoring force includes a hydrostatic head component as well as components due to a compressed gas and a distorted metal bellows.

Fig. 4 shows an improved transducer embodying the principles of this invention especially adapted for observing pressure fluctuations in pipe lines and the like. This transducer comprises a body 84, preferably of metal such as stainless steel, threaded at 86 for connection into a pipe line or other apparatus where pressure fluctuations are to be observed. A diaphragm 88 separating the fluid in the pipe line from the electrokinetic fluid is hermetically sealed into a counterbore 90, formed in the body 84, by means of a diaphragm retainer 92 threaded into the counterbore. A body insert 94, made of insulating material such as "Plexiglas," is held in place in the body 84 between the diaphragm 88 and a weather head 96 of "neoprene" or the like seated against a shoulder 98 formed in the body. A porous plug preferably in the form of a fritted glass disc 100 is cemented into a recess formed for it in the body insert. The metal diaphragm 88 serves as one of the electrodes in the electrokinetic assembly while the other electrode is a platinum wire 102 held in place by a metal contactor 104, preferably also of stainless steel, threaded at 106 into a counterbore in the insert 94. Electrical leads are connected to the body 84 and the externally projecting portion of the contactor 104.

A resilient diaphragm in the form of a short length of rubber hose or the like 108 is slipped over the body insert 94 before the transducer is assembled and fits snugly in a groove 110 prepared for it in the periphery of the body insert. The chamber for containing the electrokinetic fluid is constituted by the central bore 112 in the body insert illustrated as having a smaller diameter section 114 and a larger diameter section 116. To allow for displacement of the electrokinetic fluid relative to the plug 100 the interior of the chamber 112 is placed in fluid communication with the interior surface of the hose 108 by holes 118 and 120 drilled diametrically through the body insert. To insure that the chamber 112 is hermetically sealed at the end opposite the diaphragm 88 a gasket retainer 122, preferably also of "Plexiglas," is forced against the body insert by the contactor 104 through a gasket 124 preferably made of "neoprene" or the like.

Assembly and operation of transducer of Fig. 4

To assemble the instrument the hose 108 is slipped into place on the body insert and the fritted disc 100 is cemented into place. The body insert is then placed within the body 84 and is filled with the desired electrokinetic fluid in any suitable manner such as by immersing the entire assembly in the fluid. The contactor 104 is then screwed into place and the diaphragm 88 is placed in position, care being taken that no air is trapped inside the chamber 112. The instrument is now ready for use and when used to observe pressure fluctuations in a pipe line, for example, it is screwed into the pipe line or connecting branch thereof by means of the thread 86 so that the pressure in the pipe line acts against the outer surface of the diaphragm 88. If the pressure in

the pipe line increases the diaphragm 88 is bulged inward displacing the electrokinetic fluid, the flow of which through the electrokinetic plug 100 is reflected in the voltage appearing between the electrodes 102 and 88. The displacement of the fluid is permitted by the yielding of the hose 108 which thereby exerts the restoring force characteristic of all instruments embodying the principles of this invention. As the pressure in the pipe line decreases the electrokinetic fluid, under the urging of the distorted hose 108, tends to return to its original position passing back through the disc 100. As it passes through the disc on its return a voltage is, of course, again generated and appears across the electrodes. When the pressure in the pipe line reaches a steady state condition there is no displacement of the fluid and the streaming potential is zero. By properly selecting the materials to be used in the instrument, having due regard for such properties as mass and compliance, an instrument can be made which will respond quite accurately over wide ranges to the rate of change of pressure in the pipe line or conduit to which the instrument is applied. If it is desired to obtain a signal that is proportional to the pressure rather than to the rate of change of pressure it is necessary to integrate with respect to time. One method of doing this is by shunting the output terminals of the instrument with a condenser. A pressure change in a pipe line constitutes what can be properly called a sonic impulse or sound, although the term "sound" is more usually applied to cyclicly changing pressure especially where the frequency of variation is within the audible range. By judicious design this instrument can be made to reproduce faithfully the frequency and wave form of the pressure variations or sound occurring in the pipe line to which it is connected. Under these circumstances, where a cyclic variation of pressure occurs, the output of the instrument will be an alternating voltage. The instrument can be made to operate adequately from low frequencies approaching zero into the supersonic range. Theoretically this transducer, like almost all of the embodiments of this invention can be used to convert energy in the opposite direction. That is, instead of converting the mechanical energy of the pressure variations or sound into electrical energy it can convert electrical energy applied to the electrodes into sound or mechanical energy transmitted by the diaphragm 88. Thus if an alternating potential is impressed across the porous plug a corresponding oscillation of the fluid through the plug is produced by electro-osmosis and the instrument then operates as an electro-osmotic speaker. This invention has been so used and upon connection to the audio output of a radio receiver has been found to reproduce music and speech faithfully.

For an embodiment of the invention particularly adapted for use with sound under water reference is made to Fig. 5 which shows an arrangement known as a hydrophone including a body 126 of insulating material having a chamber 128 sealed with electrokinetic fluid therein to form a transducer with an electrokinetic assembly including a porous plug 130 and electrodes 132 and 134. The chamber 128 is sealed at one end by a thin rubber diaphragm or the like 136 and at the other end by a similar diaphragm 138. A perforated sponge rubber baffle 140 is fixed to the body 126 and covers the diaphragm 138. To stabilize the body a heavy mass such as a lead ring 142 is attached to it and can serve as a con-

venient place for the attachment of a suspending cable or rod 144. Electrical connections to the electrodes are made through the insulated cable 146.

In operation the hydrophone is suspended in water, as from a ship, and sound, as from another ship or a submarine, is supposed to impinge on the diaphragm 136 movement of which forces fluid through the porous plug 130 that is cemented or fixed in the Venturi-like throat of the chamber 128. The streaming potential generated is conducted to the surface by the cable 147. The perforated baffle 140 allows equalization of hydrostatic pressure on the diaphragms 136 and 138 but absorbs any sound which would otherwise impinge on the diaphragm 138. The heavy ring 142 firmly attached to the body 126 provides sufficient inertia to minimize the movement of the body itself under the influence of the sonic impulse.

Fig. 6 shows a diagrammatic reproduction of a phonograph pickup embodying the present invention. The body 147 of the pickup is made of an insulating material, such as a plastic, and contains an electrokinetic plug 149 and electrokinetic fluid 148. The chamber enclosing the electrokinetic plug is completed by two thin metal diaphragms 150 and 152 hermetically sealing the chamber and held in place by metal followers 154 and 156, respectively, threaded onto the body 147. The metal foil diaphragms also serve as electrodes in the electrokinetic assembly, the streaming potential being conducted from the diaphragms through their respective followers to the leads 158 running to the phonograph amplifier. The phonograph needle 160 is held by a yoke 162 of insulating material, such as plastic, cemented or otherwise suitably joined to the diaphragms. Any suitable means, such as a lug 164, are provided for attaching the pickup to a tone arm. Transverse vibration of the needle transmits mechanical energy through the yoke and diaphragms which finally appear as electrical energy traveling along the leads 158. Inertia of the tone arm to which the pickup is rigidly fastened minimizes vibration of the entire pickup assembly in response to vibration of the needle.

Fig. 7 is a diagrammatic illustration of a seismic pickup used to detect earth vibrations such as caused by earthquakes or explosions. A body 166 of light weight insulating material, such as a suitable plastic, has a chamber formed therein which is closed at one end by a diaphragm 168 and at the other end by a diaphragm 170, these diaphragms being of any suitable material, preferably thin rubber. In the central reduced portion of the chamber is located an electrokinetic plug 172 with associated electrodes 174. Diaphragms 168 and 170 are held in hermetically sealing relation with the body 166 by followers 176 and 178 respectively. Enclosing the ends of the pickup to protect the apparatus are light weight protective covers 180 and 182 which can be either friction fits on or hermetically sealed to the body 166 leaving an air space between the covers and the diaphragms. In operation the body is buried in the earth and follows the movement of the earth. The relatively heavy mass of electrokinetic fluid 184 and the mercury 186, because of inertia, tends to remain at rest thus causing a displacement of the fluid with respect to the porous plug. The streaming potential generated by this relative displacement is picked up by the electrodes 174 and conducted to any appropriate recording equipment or meter. All

though mercury is illustrated as serving to add to the inertia of the electrokinetic fluid, the device will operate with the electrokinetic fluid alone.

5 In any of the illustrated embodiments of the present invention the particular elements chosen for the electrokinetic fluid and electrokinetic assembly can be varied at will depending on structural requirements and the desired voltage output. 10 Generally speaking, in streaming potential apparatus it is desirable to have as high a voltage output as possible and therefore it is preferred to use an arrangement exhibiting a high zeta potential and a fluid having a high resistivity 15 and a high dielectric constant. For electroosmotic apparatus it is usually desirable to obtain the highest pressure difference across the electrokinetic plug for any given voltage and to accomplish this an arrangement is chosen exhibiting 20 a high zeta potential and using a fluid having a high dielectric constant. A combination of a fritted glass disc with redistilled water has been found to be quite satisfactory, particularly for use in a transducer designed for observing pressure changes on oil pipe lines. However, other materials would be obvious to those skilled in the art. For example, discs of sintered quartz have been used and other fluids have been used as, for example, a 20% solution of methyl alcohol 25 where the transducer might be used in freezing weather.

In recapitulation it can be seen that certain functional and structural characteristics appear in common in all the embodiments of the invention hereinbefore described. Looking to the structure, it is apparent that there are essentially three components viz, an electrokinetic assembly, disposed within a container or chamber a fixed quantity of fluid confined within the container 40 in such a way that part of the fluid, at least, can flow back and forth through the porous plug of the electrokinetic assembly and some means for causing a restoring force to be applied to the fluid so that when there is relative displacement between the fluid and the electrokinetic assembly 45 this force tends to restore these two components to their original relative position. This arrangement is also characterized by the fact that one of the two first mentioned components is disposed 50 in mechanical-energy transmitting relation with what might be termed a "region" external to the container. The "region" can be a tank or closed container or the like, as mentioned in the description of Fig. 1, or it can be a conduit as shown 55 in Fig. 2, or the atmosphere as shown in Fig. 3, or the sea or like body of water as in Fig. 5, or a yoke and phonograph needle as in Fig. 6, or the earth as in Fig. 7. In sum, the "region" can be substantially anything subject to a mechanical 60 disturbance including vibration, sound, pressure change and the like. All the embodiments of the invention are ideally reversible in the sense of being able to convert electrical energy either to or from mechanical energy. When the apparatus is considered as operating in the direction of transducing mechanical energy into electrical energy it will be apparent that it can be used to observe changes in any quantity which can be converted into a mechanical disturbance. 65 For example, if the region R of Fig. 1 consists of a closed bulb containing material whose volume varies with temperature, that embodiment could be designed to respond to changes in temperature. The means for causing a restoring force to be applied to the liquid upon displace-

ment thereof relative to the electrokinetic assembly can take various forms. It can include a resilient diaphragm such as the bellows of Fig. 2 and 3 or the rubber membrane of Fig. 5 or the hose 103 in Fig. 4. It can include a body of air or the like such as 78 in Fig. 3 and, it should be noted, either a diaphragm or a body of compressible gas can each be used alone without the other. Alternatively or additionally the means for causing a restoring force to be applied to the fluid can include a conduit, such as the arms of a U-tube to conduct the flow of the fluid in a direction having a vertical component. The vertical component of the direction in which the arms of a U-tube extend causes the fluid upon its displacement to exhibit a difference in head on which gravity can act to urge the fluid to return to its original position.

When the various embodiments of the invention operate in a direction to transduce mechanical energy into electrical energy either the fluid component or the electrokinetic assembly component is so disposed as to receive mechanical energy from the external region. In the embodiment shown in Figs. 1 through 6 it is the fluid component which receives the energy while the electrokinetic assembly component remains relatively stationary, whereas in Fig. 7, the fluid component remains relatively stationary and the mechanical energy is received by the body carrying the electrokinetic assembly which is thereupon, in effect, moved through or relative to the fluid. As illustrated, the diaphragms in Figs. 3 through 6 are interposed between the fluid and the external region in mechanical-energy transmitting relation. In the illustrated embodiment of Fig. 1, for example, the meniscus or free surface 24 of the fluid or the conduit 26 can be considered as placing the fluid in mechanical-energy transmitting relation with the region R.

When the apparatus is used for transducing electrical into mechanical energy the electrokinetic assembly is usually held relatively stationary and the fluid component is caused to move relative thereto by the application of an electromotive force to the electrodes.

It can be understood from the foregoing that in any embodiment which depends upon gravity to exert the restoring force it is, of course, necessary that the displacement of the fluid have only a component in a vertical direction. Thus, for example, in Fig. 1 the arms 26 and 28 of the U-tube need not extend directly vertically as long as they extend in a direction having some vertical component.

Obviously many modifications and variations of the present invention are possible in the light of the above teachings. It is therefore to be understood that within the scope of the appended claims the invention can be practiced otherwise than as specifically described.

The invention described herein may be manufactured and used by or for the Government of the United States of America for governmental purposes without the payment of any royalties thereon or therefor.

What is claimed is:

1. A container, an electrokinetic assembly within said container including a porous plug and a pair of electrodes, one on each side of said plug, a fixed quantity of fluid confined within

said container in contact with said electrodes in a position to oscillate, in part at least, through the porous plug of said assembly, a surface of said fluid located in that portion of the fluid disposed to one side of said plug being in mechanical-energy transmitting relation with a region external to said container, and means in contact with the portion of the fluid on the other side of said plug for applying a restoring force to said fluid upon displacement of said fluid relative to said electrokinetic assembly.

5 2. A container, an electrokinetic assembly within said container including a porous plug and a pair of electrodes, one on each side of said plug, a fixed quantity of fluid confined within said container in contact with said electrodes in a position to oscillate, in part at least, through the porous plug of said assembly, said fluid being in mechanical-energy transmitting relation with a region external to said container, and means for causing a restoring force to be applied to said fluid upon displacement of said fluid relative to said assembly.

15 3. A container, a component including an electrokinetic assembly within said container, said assembly comprising a porous plug and a pair of electrodes, one on each side of said plug, a second component constituted by an electrokinetic fluid of fixed quantity confined within said container in contact with said electrodes in a position to oscillate, in part at least, through the porous plug of said assembly, one of said components being in mechanical-energy transmitting relation with a region external to said chamber, and means for causing a restoring force to be applied to said fluid upon displacement of said fluid relative to said assembly.

20 4. The device of claim 1 wherein a diaphragm is interposed between said fluid and said external region and wherein said restoring force means includes a resilient diaphragm.

25 5. A method of transducing electrical and mechanical energy between the electrodes of an electrokinetic assembly and an external region, said assembly comprising in addition to said electrodes a porous plug disposed between said electrodes, said method comprising the steps of (1) subjecting to relative displacement said assembly and a fixed quantity of liquid confined to oscillate in part at least through the plug and in contact with said electrodes, said displacement being in mechanical-energy-transmitting relation with said external region, and (2) imposing on said fluid a restoring force whose magnitude is a monotonic increasing function of the displacement of said fluid relative to said assembly.
